ADAPTOR FOR A CAPLESS ELECTRIC LAMP

Thomas Hammond, Cobham, England, assignor to Rival Lamps Limited, Weybridge, England, a British company

Filed May 22, 1967, Ser. No. 7,215

Claims priority, application Great Britain Dec. 30, 1966

Term of patent 14 years

(Cl. D26—1)

Fig. 1.

Fig. 2.

Fig. 3.

Fig. 4.

Fig. 5.

Fig. 6.

FIGURE 1 is a front elevation of an adaptor for a capless electric lamp, showing my new design, the side opposite that shown being a mirror image thereof;

FIGURE 2 is a side elevation thereof the side opposite that shown being a mirror image thereof;

FIGURE 3 is a top plan view thereof;

FIGURE 4 is a bottom plan view thereof;

FIGURE 5 is a section taken on line 5—5 of FIGURE 2; and

FIGURE 6 is a section taken on line 6—6 of FIGURE 1.

I claim:

The ornamental design for an adaptor for a capless electric lamp, substantially as shown and described.
